(57) **CLAIM**

The ornamental design for a charging case, as shown and described.

DESCRIPTION

FIG. 1 is a top, front and right side perspective view of a charging case showing our new design;

FIG. 2 is a bottom, rear and left side perspective view thereof;

FIG. 3 is a front, elevation view thereof;

FIG. 4 is a rear, elevation view thereof;

FIG. 5 is a left, side elevation view thereof;

FIG. 6 is a right, side elevation view thereof;

FIG. 7 is a top plan view thereof; and,

FIG. 8 is a bottom plan view thereof.

The broken lines depict portions of the charging case in which the design is embodied that form no part of the claimed design.

1 Claim, 8 Drawing Sheets
